PACKAGE INSERT ADAPTABLE FOR THE MOUNTING OF FINE FILAMENTOUS THREAD IN ANNULAR PACKAGE FORM

Charles A. Huttinger, Lakewood, Ohio, assignor to Acme Rayon Corporation, Cleveland, Ohio, a corporation of Ohio

Application April 3, 1936, Serial No. 72,480

5 Claims. (Cl. 18—8)

My invention particularly relates to improved forms of inserts adaptable for mounting fine filamentous rayon thread in annular package form, such as cakes, wound spools, wound bobbins, and other annular packages of symmetrical or balanced formation, for the purpose of liquid treating the thread. The rayon thread is collected in such annular package forms by spinning machines from the precipitating bath in which the rayon filaments are set up. The rayon thread as so collected comprises a comparatively large number of filaments which are twisted as some forms of packages are being collected and are collected untwisted in other forms of packages. My invention is an improvement upon the forms of package inserts shown, described and claimed in my pending application, Serial No. 724,114.

The treatments to which the rayon packages are subjected by my improved apparatus are those to which the rayon is necessarily subjected, before the precipitated and package-collected thread can be considered a final product ready for the market, such as various water washings, desulphurizing, bleaching, oiling, szing, dyeing, drying and other purifying and finishing operations. For purposes of illustration, I show in the accompanying drawing and herein describe two forms of my improved insert which serve to support a cake of rayon while the same is being subjected to the above-mentioned operations.

The objects of the invention are to effect the aforesaid operations in a thorough manner and economically, and without breaking or otherwise materially damaging the thread, while at the same time preventing the creation of any immobile areas in any portion of the package, or unequal strains in different portions of the package, either during the liquid treatments or during the drying of the package, which immobile areas and strains result in a non-uniform dyeing of the thread of the package. The obviating of the creation of immobile areas and strained conditions in the package produces even shrinkage during the drying of the package. This even shrinkage is obtained by even one drying operation, thereby obviating the necessity of rewetting the package and again drying it in order to improve the uniform shrinkage factor. Furthermore, if some portions of the package dry in an immobile condition, or have strains set up therein by some of the purifying and drying operations, antecedently to the dyeing thereof, different portions of the thread in the package then have different reflective indexes and give different color reactions or have barred effects when the thread

is dyed, resulting in a thread of non-uniform color.

Primarily, my improved insert effects the loosening up of the package, when treating the latter in its initial collected form, so as to provide for all parts of the package their respective natural scopes of free play, relative to other parts of the package, thus effecting a natural alteration of the relative positions of all the thread strands comprising the package. The purification of the package and the other treatments thereof are carried out without unduly impairing the tenacity and elasticity of the thread required for later handling and processing or use, and without setting up local tension areas or non-uniform strains.

In effecting the aforesaid advantage, my improved inserts permit the pulsating of the package body by means of treating liquid in that the package, while mounted upon the insert, is free to move to a predetermined extent in, and under the action of, the treating liquid. The improved inserts provide for so mounting the package that different portions thereof move or pulsate differently under the action of the treating liquid; specifically, spaced transverse portions of the package react differently than the package portions intermediate said spaced transverse portions.

Improved processes of liquid-treating rayon packages, and apparatus therefor, are shown, described and claimed in my pending application, Serial No. 724,113, and the improved inserts of the instant application are adaptable for use in working such processes. It is designed in such improved processes that the direction of flow of the treating liquid shall be, or at least may be, periodically reversed, thus to pass the liquid alternately in both directions through the package body, from inside out and outside in, or at least the treating liquid penetrates the package body and tends to pass through alternately in both directions. The treating liquid is passed through the package body under any desired practicable pressure so as thereby to control to an extent the character of the treatment and the character and amount of package movement and pulsation, and the pressure may be maintained uniform or may be varied. Although the range of practicable pressures is considerable, particularly by reason of the different effects of different treating liquids, I preferably use a nominal pressure of from one to two pounds. My improved inserts are of split formation, so as to provide for the convenient insertion thereof within the rayon

package, in order to mount the package thereon for treatment without damaging the thread of the package, but the liquid pressures used in the liquid treatments are not great enough to materially expand or compress the split inserts, so that the latter provide a substantially rigid support of constant dimension during the liquid treatments. Furthermore, as clearly shown and described in said pending application, Serial No. 724,113, a plurality of inserts are tightly locked together in a vertical tier, so as to hold the inserts rigid during the liquid treatments, with a rayon package mounted for treatment on each one of the inserts.

15 When the treating liquid passes from without the tubular package through the body thereof and into the interior of the package, my improved inserts provide for a deforming of the package by permitting portions thereof to move inwardly 20 a predetermined distance under the pressure of the treating liquid, so as to loosen up the package to a degree and permit an altering of the positions of the strands or different portions of the thread comprising the package. When the treating 25 liquid passes from within the package outwardly through the body thereof, the deformed package portions are moved back into their original collected form, or tend so to move, so that these package portions are pulsated or have to-and-fro 30 movements under the action of the reversible liquid flow.

It is well understood by those skilled in the art, that rayon packages of the character herein described are spun so that the strands thereof 35 prevent any substantial enlargement of the package perimeter. Therefore, the pressure of the treating liquid from within the package outwardly, under any pressures practicable usable, do not bulge or deform the package outwardly so as to increase its perimeter to any material extent. However, those portions of the package which are not moved inwardly by liquid passed inwardly of the package body are adjusted somewhat outwardly during such treatment, as clearly shown in the accompanying drawing and as will be hereinafter fully described.

The improvements in the forms of inserts shown, described and claimed in the instant application, over those shown, described and claimed in my said pending application, Serial 50 No. 724,114, consist in means for more uniformly liquid treating the rayon package, specifically, these improvements comprise means for permitting the passage of the liquid through the 55 insert elements which define the several package portions that are differently deformed by the treating liquid. These elements, as shown in said application, Serial No. 724,114, consist of insert bars, bobbin plates, etc., between each 60 adjacent two of which are provided elongated lengthwise openings through which transversely spaced portions of the package defined by such bars and plates are pulsated. Radially exterior of these bars or plates are certain package areas 65 which do not receive efficient and satisfactory liquid treatment. Therefore, I have devised forms of inserts shown and described in the instant application which provide for the passage of liquid through the bodies of the spaced 70 bars and plates whereby to permit the thorough liquid treatment of the rayon package areas immediately exterior of such bars and plates.

The annexed drawing and the following description set forth in detail certain means exemplifying my improved forms of package in-

serts, such means constituting, however, only a few of the various forms in which the principle of the invention may be embodied.

In said annexed drawing:

Figure 1 is a lengthwise section of one form 5 of my improved insert, showing a rayon cake mounted thereon for liquid treatment;

Figure 2 is a transverse section, taken in the plane indicated by the line 2—2, Figure 1, this view showing the cake in the form in which it is collected by the spinning machine or, if it has been deformed by a treating liquid passed therethrough previously from without the package inwardly, in the form in which it re-establishes itself or tends to be so re-established, when the 15 treating liquid is passed through the cake from within outwardly;

Figure 3 is a view similar to Figure 2 but showing the forms assumed by the different cake portions, or which they tend to assume, when 20 the treating liquid is passed through the body from without inwardly;

Figure 4 is a view, on an enlarged scale, of a portion of the showing of Figure 1;

Figure 5 is a perspective view of a second form 25 of insert embodying my improvements;

Figure 6 is a transverse section of the insert shown in Figure 5 with a cake mounted thereon for liquid treatment, this view showing the cake in the form in which it is collected by the spinning machine, or, if it has been treated by a liquid passed therethrough previously from without inwardly, in the form in which it re-establishes itself, or tends to re-establish itself, when the 30 treating liquid is passed therethrough from within outwardly; and

Figure 7 is a view similar to Figure 6 but showing the forms assumed by the different portions of the package body, or the forms which they tend to assume, when the treating liquid is 40 passed through the package from without inwardly.

Both forms of improved inserts shown and described provide for efficient and satisfactory liquid treatment of those package areas radially 45 exterior of the spaced bars and plates or equivalent means between adjacent deformable areas, but the claims of this application are directed to that form of improved insert shown in Figures 1 to 4.

Referring to the annexed drawing in which the same parts are indicated by the same respective numbers in the different views, and particularly referring to Figures 1-4, an insert 1 consists of an annular shell having a multiplicity 55 of ports 2 through the wall thereof, said ports preferably being arranged in a series of lengthwise rows and a series of transverse rows, as clearly shown in Figure 1. These ports 2 provide means for liquid communication between the 60 interior and exterior of the shell body. Secured to the exterior surface of the insert 1 by rivets 4 are a plurality of non-corrosive bars 3, preferably spaced longitudinal outwardly extended hard rubber bars. These spaced bars 3 provide 65 spaced elongated lengthwise openings 8 between the adjacent bars 3 when a cake package 7 is mounted upon the bars 3. When the treating liquid is passed through the package 7 from without inwardly the cake portions 9 between 70 the respective adjacent bars 3 are moved inwardly until they contact with the portions 12 of the insert body. The portions 10 of the cake body immediately exteriorly of the bars 3 cannot be moved inwardly but, in fact, adjust 75

themselves slightly outwardly, as indicated by the areas 11, Figure 3. When the treating liquid is passed through the package body 7 from within outwardly, the cake portions tend to 5 re-establish themselves in the position shown in Figure 2. During the early stages of the liquid treatment, the time or pressure of application thereof, or the density of the package body, may be such, as not to permit entire penetration of 10 the package body 7 by the treating liquid, so that the package portions 9 will only tend toward the positions shown therefor in Figures 2 and 3, and the package portions 10 likewise.

In order that the package areas 10 may receive 15 liquid treatment uniformly with the package portions 9, I provide the bars 3 with ports 5 which have liquid communication with the interior of the insert 1 and with the package body areas 10. Preferably, I arrange the ports 5 to register with 20 all of the ports in the adjacently lengthwise row of insert ports 2. That is, the ports 5 of each of the bars 3 register with all of the ports of one lengthwise row of ports 2 and with one of the ports of each transverse row of ports 2. Furthermore, I preferably enlarge the outer ends 25 of the ports 5 so as to provide ready and thorough distribution of the liquid from the ports 5 into the package bodies 7 when the liquid flow is from within outwardly and so as readily and thoroughly to direct the liquid flow from the package body 7 into the ports 5 when the direction of the liquid flow is from without inwardly.

The several insert portions 12 form stops limiting the amount of inward movements of the 30 cake portions 9.

By the means described, a thorough liquid treatment of the package portions 10 is secured, together with the thorough treatment of the package portions 9.

40 In Figures 5, 6, and 7, I show a form of insert, preferably of non-corrosive metal, which is polygonal in cross-section and by the use of which are effected the advantageous liquid treatments of rayon packages above-mentioned. The particular insert structure shown in these figures is 45 pentagonal in cross-section. The cake package 15 is mounted upon the exterior surface of the pentagonal insert 16 which latter is of such size that the inner face of the package 15 closely 50 contacts the corners 19 of the insert, thus leaving openings 20 between each two adjacent corners 19, into which openings 20 the spaced portions 21 of the package 15 are forced by the pressure of a treating liquid passed through the package from without inwardly, as clearly indicated in Figure 7, the areas 22 of the package 15, which are adjacently exterior of the corners 19, being forced slightly outwardly during such action, as indicated by the areas 24, Figure 7. The 55 several plane insert portions 23 form stops limiting the amount of inward movements of the package portions 21. When the treating liquid is passed through the package 15 from within the insert 16, the package 15 tends to assume its original collected form, as clearly indicated in Figure 6. The insert 16 is formed with a multiplicity of ports 17, which ports are preferably arranged in a series of transverse rows and a series of lengthwise rows, Figure 5. In order

that the areas 22 of the package 15 may be efficiently liquid treated, as well as the spaced comparatively large areas 21, certain of the ports 17 are disposed in the angles 19 of the insert, as indicated by the ports 18. Preferably, one of the lengthwise rows of ports 17 is intersected by each angle 19 of the insert 16, and each angle 19 also intersects one port of each of the transverse rows of ports 17.

By the means described, a thorough liquid treatment of the package portions 22 is secured, together with the thorough treatment of the package portions 21.

The pulsating of the rayon package during liquid-treatment which is occasioned by the use of 15 my improved package inserts, and the consequent loosening-up and porosity of the package, give all portions of the latter full opportunity to contract when drying, in accordance with their several tendencies, without occasioning any strain in any 20 portion of the package. By "pulsating" I mean the inwardly and outwardly to and fro movements made by the package and the constituent parts thereof during the liquid-treatment of the package upon my improved inserts.

25

What I claim is:

1. Package inserts adaptable for the mounting of fine filamentous thread in annular package form comprising a shell provided with a multiplicity of ports and with spaced outwardly-extended bars whose inner edges are rigidly secured to the shell, said bars being provided with ports having liquid communication with the interior and exterior of the shell.

2. Package inserts adaptable for the mounting of fine filamentous thread in annular package form comprising a shell provided with a multiplicity of ports and with spaced outwardly-extended non-corrosive bars whose inner edges are rigidly secured to the shell, said bars being provided with ports having liquid communication with the interior and exterior of the shell.

3. Package inserts adaptable for the mounting of fine filamentous thread in annular package form comprising a shell provided with a multiplicity of ports and with spaced outwardly-extended rubber bars whose inner edges are rigidly secured to the shell, said bars being provided with ports having liquid communication with the interior and exterior of the shell.

4. Package inserts adaptable for the mounting of fine filamentous thread in annular package form comprising a shell provided with a multiplicity of ports and with spaced outwardly-extended bars whose inner edges are rigidly secured to the shell, said bars being provided with ports therethrough having liquid communication with some of the shell ports.

5. Package inserts adaptable for the mounting of fine filamentous thread in annular package form comprising a shell provided with a multiplicity of ports and with spaced outwardly-extended bars, said bars being provided with ports therethrough having liquid communication with some of the shell ports and each formed to distribute and drain liquid to and from an area greater than its cross-sectional area.

CHARLES A. HUTTINGER.
